VERTICAL CONVEYER OVEN

Charles A. Barnett, Cleveland Heights, and Harry W. Steindorf, Cleveland, Ohio, assignors to The Foundry Equipment Company, Cleveland, Ohio, a corporation of Ohio

Application May 5, 1930. Serial No. 449,957

4 Claims. (Cl. 34—12)

This invention relates to vertical ovens of the type having the work carried through on a continuously moving conveyer at speeds such that loading and unloading can be effected while the 5 conveyer elements pass openings in the oven structure, and particularly relates to core baking ovens, although not limited thereto. Among the purposes of the invention are greater facility of loading and unloading with generally more efficient organization of work at these points than has previously been possible; economical and efficient regulation of heat; application of heat to the work by convection as well as by radiation; supply of air to oxidize the work; removal of 10 spent gases; arrangements for making minor repairs and adjustments without stopping the conveyer or interfering with loading and unloading.

Although we herein show and describe a preferred embodiment of our invention, as constructed for heating from an internal firebox, and as modified for electrical heating, it is to be understood that these are for purposes of illustration and not of limitation and that the principles are susceptible of other application.

25 In the accompanying drawings, Fig. 1 is a vertical section with the near wall removed; Fig. 2 is a horizontal section, partly in plan, on the line 2—2 of Fig. 1; Fig. 3 is a partial vertical section on the line 3—3, Fig. 1, but somewhat enlarged; Fig. 4 is a diagrammatic horizontal section on the line 4—4, Fig. 1, showing arrangements for loading and unloading; and Fig. 5 is a vertical section corresponding to Fig. 1 but showing the furnace modified for electric heating.

35 Referring now to Fig. 1, our oven comprises a tower-like structure which may conveniently be built of an angle bar frame with its footings in a concrete foundation 1 which forms the floor of a pit 2 below the plant floor level 3. The 40 frame is open in the pit and up to a point about six feet above the floor 3, but the remainder of the tower is suitably walled with a heat-insulated casing 4 and outside metal sheeting, or the like, all of known construction, stopping high enough 45 above the floor level 3 to allow full headroom. A chain conveyer, shown in somewhat diagrammatic style and generally indicated at 5, carries trays such as 6 up in one side of the structure and 50 down in the other side, movement being imparted by a head sprocket 7 which turns in the direction of the arrow. A bottom return guide 8 takes up and tensions the chain. The exact construction of the conveyer does not form a part of the 55 invention and therefore only such conveyer fea-

tures as directly cooperate with our invention will be described in further detail.

In the following description and in the claims, the entire apparatus is considered as divided into zones, according to the operations which take place along various parts of the conveyer path. Thus the portions of the apparatus adjacent the path A—B, constitute the loading zone, from B up and around to C is the heating zone, from C to D is the first cooling zone, or work cooling zone, 65 from D to E the unloading zone, and from E to A the second cooling zone, or cooling zone for work holders. The zones A—B and D—E, taken together are referred to as the work-handling zone.

70 Although there is a direct cooperation between the thermal arrangements and the work-handling arrangements, as will become apparent later, they may be more conveniently described separately.

Heating system

The furnace 10 is supported on suitable elements of the framing, having its bottom a little above the bottom of the casing 4. The furnace 80 consists of a combustion chamber or fire-box 11, preferably oil or gas fired as by a burner 12, the fire-box being made of the usual refractory materials, and having a perforated roof 13. The combustion chamber is surrounded except at the 85 ends by a diffusion chamber 14, also of refractory material, and also having a perforated roof 15. Air from a blower 16, mounted outside the casing 4 is carried by a duct 17 into a flue 18 beneath the combustion chamber 11, and passes out and 90 up around the side walls of the combustion chamber and mixes in the diffusion chamber with the products of combustion, thence rising through the perforations in the roof 15 into the heating zone. This supply of air serves to reduce the 95 heat of the combustion chamber, about 1500° to 1800° F. to a suitable temperature for baking, but not burning the material on the conveyer, about 350° F. to 600° F. for cores. At the same time, the excess of air provides oxygen for oxidizing the cores. By reason of the thorough diffusion and because of recovery of heat from outgoing work, as will be described below, a large oven can be operated with a small combustion chamber and very economical use of fuel.

100 The hot air from the combustion chamber rises between a heat-insulating wall 20 and a short non-insulated wall 21, the former constituting part of the inner side of a passage for outgoing work and the latter constituting part of the in-

ner side of a passage for incoming work. Damp-
er gates 22, regulable from outside the oven, con-
trol the intensity of application of heat to the
new work.

5 For efficiency and for accurate temperature
regulation it is necessary to prevent any large
inflow of air to the heating zone except through
the duct 17. To accomplish this, a false wall
23 is placed adjacent the path of the conveyer
10 opposite the diffusion chamber wall 10, thus nar-
rowing the passage to just clear the conveyer
trays 6. These may be either solid plates or
closely slatted racks. The narrow passage or
throat is of a length greater than the distance
15 apart of two successive conveyer carriers, so that
the throat is always blocked by one or more
of the trays 6, with the result that only an in-
consequential amount of air can enter. A similar
throat is formed on the outgoing side by false
20 walls 24, but this is located considerably higher
than the incoming throat.

The insulated inner wall 20 stops at a point
opposite the upper end of the false walls 24, but
the inner of these false walls is continued up
25 as at 25 with an inward inclination to about the
bottom of the headwheel 7, to prevent short-
circuiting of heat currents to the outlet flues 26
and stack 27.

It results from the above arrangement that
30 heat is applied to the cores by convection rather
than by radiation, thereby giving uniform treat-
ment to all the cores. Convection heating is
particularly important where there is a direct
radiant heat supply adjacent the work, as in
35 electrically heated furnaces. Unless convection
currents are set up in such furnaces the bak-
ing is uneven because the work next to the heat-
ers gets most of the heat and shields work in
the rear which consequently is insufficiently
40 heated.

Several vertically separated outlet flues 26, each
having its individual damper 28, controlled from
the floor, carry spent gases from the discharge
45 side of the upper part of the heating zone to a
stack 27. A lively draft is provided without the
necessity of a tall stack by the exhausting ef-
fect of a nozzle 29 above the topmost flue 28.
This nozzle is supplied with a portion of the air
50 taken off the duct 17.

It will be observed from the foregoing that
work coming in past the constriction 23 is ex-
posed somewhat gradually to the baking heat,
according to the degree of opening or closing
55 of the damper gates 22. By reason of the slow
travel of the conveyer, the work is well heated
by the time it is exposed, above the baffle 21,
to the full blast from the diffusion chamber.

Cooling system

60 After the work has been baked it passes out
of the heating chamber through the throat
formed by the false walls 24. At this point the
work begins to be shielded from the heat by the
upper part of the insulated wall 20. Below the
65 walls 24 and suction nozzle 35 of the blower 16
is connected over several apertures 36 in the cas-
ing 4, and the outgoing passage is widened at
and below this point sufficiently to permit air
70 to flow past the conveyer trays therein in quan-
tities adequate to the capacity of the blower.
The open construction of the bottom of the tower
permits free access of air from the room into
the outgoing passage, with the combination of
75 several desirable results; namely, the cooling of

the work so that it can be handled when it reaches
the unloading opening 40, the preheating of the
air supplied at 18 to the diffusion chamber 14,
and bringing fresh air constantly to the unloading
and loading stations, thus maintaining com-
fortable conditions for the workmen there. 80

In operating our apparatus as a core oven, the
cores are removed during the travel from D to E,
but the core plates and core dryers are left on
the trays 6. For reasons that will be explained
hereafter, it is necessary to cool these to a tem-
perature lower than that at which the cores can
be unloaded. Diffusion of heat from the plates
and dryers during the travel from E to A ac-
complishes this result. 85

The bottom take-up of the conveyer is an ad-
justable frame located below the level of the
floor 3, and having semi-circular guides 41 for
the conveyer chain, sufficiently above the floor
of the pit 2 for the conveyer trays to clear. On
account of the slow travel of the conveyer, ad-
justments and minor repairs can be made in the
pit without stopping the machinery. For ex-
ample, a tray can be removed and a new one
hooked on in the zone. 95

Loading and unloading

A difficulty previously encountered with verti-
cal ovens has been to find space for a sufficient
number of core-makers to work and have access
105 to the loading side of the conveyer, without get-
ting in one another's way. We accomplish this
by the arrangement of the handling zone fea-
tures, and by leaving the core plates and dryers
on the conveyer from the unloading back to the 110
loading side.

Referring now to Fig. 4, the core-makers are
stationed at benches 45, 46 on the floor 3 on
three sides of the oven. As the conveyer trays
6 come up to the openings 47, 48, the core-
makers, moving as generally indicated by the
arrows, take off the empty plates and dryers
115 for their individual work and load new work
on. The cores, on the down travel of the trays,
have been unloaded through the opening 40 by
a man, wearing heavy gloves, whose station is
indicated at 51. The core-makers must work
with bare hands; thus, if it were not for the
second cooling zone E—A, it would be necessary
120 to take off the core plates and dryers also at
51 and set them to one side to cool before they
could be used, so that the zone E—A saves extra
handling and saves floor space which would
otherwise be necessary to hold the cooling plates
125 and dryers. A grating 49 continues at the floor
level across the pit 2, so that the men at the
benches 45 work from the inside through the
opening 48, Fig. 1, while those at the benches 46
work through the outside opening 47. Outer
130 and inner casings 50 guard the conveyer shafts. 135

Electric furnace

In constructing this type of furnace for electric
heating, or for any sort of heating where the
heat is from radiant sources on the sides of the 140
conveyer pathway instead of from a firebox, cer-
tain modifications may be made in details, as
shown by Fig. 5.

In Fig. 5 the construction and principles of op-
eration are fundamentally the same as for the 145
forms in the other figures, but the omission of
the firebox necessitates some changes in detail.

The space between the incoming and outgoing
conveyer passageways, which in the form of Fig.
1 is closed by the bottom of the furnace struc- 150

ture, is closed in the present form by a horizontal flooring 100.

The conveyer trays pass up from the loading zone A-B between the two sides 118 and 118' 5 of a recirculating duct 117 into a passage extending approximately to the sprocket wheel 107, which passage is formed by a series of vertically superposed electric heaters 111 which may conveniently be set edgewise with small intermediate 10 air spaces.

A baffle wall 120-125 extends from slightly below the axis of the sprocket 107 to the bottom of the cooling zone, being bent toward the center of the furnace at the top to allow the downward 15 passage of conveyer trays, and being vertically disposed further down opposite a false wall 124, thereby forming a throat through which the conveyer trays 6 pass downward in their entrance to the cooling zone C-D. The wall portion 120 20 below the throat is heat-insulated and is spaced somewhat inward from the line of movement of the inner edges of the conveyer trays to allow circulation of incoming air for cooling around the trays, the outer wall 104 of the furnace structure 25 being similarly related to the tray path.

A fan 116 taking air from the top of the cooling zone through a duct 136 recirculates the air through the passage 117 to the ducts 118-118' as already mentioned.

30 The stack 127 allows hot air and the gases which result from the baking operation to escape. Since this furnace has no gases of combustion to be handled and no fire to be supported, it is not necessary to provide a blast in the stack, 35 although a blast such as illustrated in Fig. 1 could be provided for if necessary. Such might be the case if, for example, rows of gas flames should be used instead of the heaters 111.

The recirculation of air in this electric furnace, 40 besides providing oxygen to oxidize the binder used in making the cores, also causes uniform baking of the cores for the reason that the heat is applied by convection and not solely by direct radiation. The use of convection heat currents 45 is particularly necessary in this type of furnace, as otherwise the work next to the heaters would receive the greater part of the heat and cut it off from the work in intermediate positions on the trays, and indeed the work directly exposed to 50 the heat would be baked more on one side than the other. A good circulation of air, as we have provided for, avoids these disadvantages.

As in the firebox type of furnace, the recirculated air also reduces the amount of heat which 55 must be primarily applied and diffuses the heat.

The division of this furnace into zones, loading and unloading arrangements, and the conveyer construction are the same as in Fig. 1.

Operation

60 The operation is believed to be apparent from the foregoing description, but will be briefly reviewed.

The cores are loaded onto both sides of the 65 conveyer at the openings 47 and 48 as each tray 6 slowly travels from A to B. Approximately at B the work enters the heating zone, but is exposed gradually, being shielded from the direct blast of hot air and gas at first by the wall 10 70 and later by the wall 21. If it is advisable to apply the full heat earlier, one or more of the damper gates 22 can be opened.

The air from the diffusion chamber 14, which 75 has been heated from the firebox 11, is forced by the baffle 25 to follow the conveyer path to

the outlet flues 26 and travels down a greater or less distance according to whether the various dampers 28 are open or closed. This air, forced in by the blower 16, provides the oxygen necessary to oxidize the cores during baking, but part 80 of the stream is diverted to supply the exhaust at 29.

At the walls 24 the work starts out of the heating zone, and as it passes the blower suction opening 35 comes into a cooling current so that 85 at the point D it can be taken off by the unloader, wearing heat-proof gloves.

The core plates and dryers are still too hot to be moved with bare hands, but further travel from E down under and up to A gives them time 90 to cool, so that each coremaker, working with bare hands, can take off his own, and he also has time, before the tray rises to B to load on the new work. The grating platform 49 and inside opening 48, allow some of the coremakers to get 95 to the trays at one side, while others are standing on the floor 3 and handling material through the opening 47 at the other side.

Other modes of applying the principles of our invention may be employed instead of the one 100 explained, change being made as regards the mechanism herein disclosed, provided the means stated by any of the following claims or the equivalent of such stated means be employed.

We therefore particularly point out and distinctly claim as our invention:

1. A vertical conveyer oven comprising, in combination, an upper casing and a lower portion open to the atmosphere and for work-handling on both sides of the upward and downward runs of 110 the conveyer, a conveyer having a path of travel through said casing and said open portion, heat-supplying means in said upper casing, heating and cooling zones in said upper casing, a work-handling zone in said lower portion, means for 115 drawing atmospheric air through said handling zone and past work moving through said cooling zone.

2. In a vertical conveyer oven comprising a casing having a conveyer therein adapted for continuous movement up one side and down the other, heating and air-circulating means applied to said conveyer, including as a source of heat a diffusion chamber within the casing, a combustion chamber within the diffusion chamber, 125 means for extracting heat from outgoing work and returning the same to the oven by a current of air to maintain combustion and to oxidize the work.

3. In a vertical conveyer oven comprising a 130 casing having a conveyer therein adapted for continuous movement up one side and down the other, heating and air-circulating means applied to said conveyer, including as a source of heat a diffusion chamber between the upward and 135 downward conveyer runs, a combustion chamber within the diffusion chamber, single means for supplying air to said combustion chamber, for mixing additional air with combustion products, and for extracting heat from outgoing work. 140

4. In a conveyer oven having lines of conveyers passing one another in opposite directions, means of access to both lines from within and without the boundaries of the oven, said means being constantly open and means for 145 maintaining said means of access at prevailing room temperatures.

CHARLES A. BARNETT.
HARRY W. STEINDORF.
